TOY WITH DISPLACEABLE ELEMENTS IN
TRANSPARENT ENCLOSURE

Alfred A. Anthony, Rye, N. Y.

Application March 4, 1949, Serial No. 79,566

4 Claims. (Cl. 46—1)

1

This invention relates to toys in which a group of separate displaceable elements can be moved selectively between different sockets in which they rest. Elements of different colors are associated with different sockets, but can be shifted into any of the sockets.

One object of the invention is to provide a toy for small children in which a child can operate keys to make balls or other elements jump up and out of sockets in a base, but the displaceable elements are confined within a transparent chamber so that they can not fall on the floor and so that the child can not put them in his mouth.

Another object of the invention, for older children, is to associate the different displaceable elements with certain sockets in the toy, as by having the displaceable elements of different colors corresponding to different colored sockets. The toy can be used by distributing the elements in haphazard fashion among the different sockets and then operating the actuator levers to shift the elements around in the enclosure with a view of getting each element into the socket of corresponding color.

One feature of the invention relates to the shape of the cover so as to provide a sloping surface against which the elements can be projected to deflect them sidewise across other sockets of the toy. This prevents the element from dropping back into the same socket from which it was projected, as would be the case if the top of the cover were horizontal.

Other features of the invention relate to the construction of the toy with a minimum number of moving parts and with the levers notched and engaged by portions of the base so that the toy can be assembled without any pivot pins and with a minimum of labor, the cover serving as a retainer for holding all of the operating levers assembled with the base.

Other objects, features and advantages of the invention will appear or be pointed out as the description proceeds.

In the drawing, forming a part hereof, in which like reference characters indicate corresponding parts in all the views,

Figure 1 is a front view, partly in section, showing a toy embodying this invention.

Figures 2 and 3 are sectional views taken on the lines 2—2 and 3—3 respectively, of Figure 1.

Figure 4 is a fragmentary sectional view taken on the line 4—4 of Figure 3.

The toy comprises a base 10 which is preferably a one-piece plastic moulding. The base 10

2

has a lower edge portion 11 that rests on a table or other support. The base is shaped to provide a row of sockets 13 separated from one another by walls 14. Each of the sockets is preferably longer than it is wide.

In the construction illustrated, each of the sockets 13 contains a displaceable element comprising a ball 15 having a diameter slightly less than the width of the socket and substantially less than the fore and aft length of the socket. Displaceable elements of other shapes than spheres can be used.

There is an actuator comprising a lever 17 extending across the lower portion of each of the sockets 13, and these actuators 17 are preferably of different colors. Each of the balls 15 is preferably colored to correspond with one of the actuators or levers. No other coloring of the sockets is necessary because the actuators 17 are of broad extent and may be almost as wide as the respective sockets with which they are associated.

There is a wall 20 extending across the front of all of the sockets 13. This wall forms the front wall of each socket. There is a separate recess 22 in the top of the wall 20 at the front of each of the sockets 13. These recesses are not as wide as the actuators 17; and there are notches 23 in the opposite side edges of each actuator in position to be engaged by the sides of the recess 22, the width of each actuator 17 between its notches 23 being somewhat less than the width of the recess 22. Each actuator 17 rests on the wall 20 at the bottom of its associated recess 22, and the bottom of the recess serves as a fulcrum on which the lever 17 can be rocked.

Each of the sockets 13 has a bottom 25 (Fig. 3) which need not be continuous, on which the rearward end of the actuator 17 rests. It is a feature of the construction that the socket bottom 25 is slightly lower than the bottom of the recess 22 so that the actuator 17 slopes downward toward the rearward end of the socket and the ball 15 resting on the actuator 17 rolls along the sloping actuator 17 and into contact with a wall 27 at the back of the socket. The advantage of this construction is that the ball 15 remains at a maximum distance from the fulcrum of the actuator when at rest. Operation of the actuator 17 by tapping its forward end or key portion downward gives the portion of the actuator that is in contact with the ball a maximum displacement for projecting the ball 15 upward and out of the socket.

There is a dome or cover 30 attached to the base

10 and extending across all of the sockets 13. This dome or cover 30 has a lower edge portion 32, and at least a portion of the length of the lower edge 32 fits into a groove in the base 10 for holding the cover 30 against transverse displacement on the base. The cover 30 is permanently secured to the base by cement or any other fastening means along the part of the edge portion 32 that contacts with the base 10.

The cover 30 is preferably shaped with substantially parallel front and rear walls 33, and a top 35 of continuous curvature. The top 35 of the cover is preferably curved in a fore and aft direction as well as transversely so as to provide a shape of pleasing appearance. In the preferred construction the cover 30 is made of transparent plastic material. Although the cover 30 is preferably of one-piece construction and transparent throughout its full extent, it is sufficient to have merely the front of the cover 30 transparent in order to permit the child to see the balls 15 at all times.

When the cover 30 is made longer than the row of sockets 13, as is the case of the construction illustrated, the portions of the base 10 that are under the cover 30 but beyond the sockets are made with a surface 37 which slopes toward the nearest socket 13, or the portions of the base beyond the sockets and under the cover 30 can be limited to a projected horizontal dimension less than the radius of the ball 15 so that the balls cannot stand on these surfaces. With such construction, the balls will always roll into any adjacent empty socket. The sockets are purposely made with their fore and aft length less than twice the diameters of the balls so that each socket is too short to hold two balls at once.

Another feature of the cover 30 is that its inside surface above the sockets 13 slopes with respect to the horizontal, except at the extreme top of the cover 30. This slope causes balls to be deflected sidewise when they are projected upward against the cover 30, and it is this deflection that causes a ball projected out of one socket to drop into another socket, or on top of balls resting in other sockets.

With small children, the noise produced by making the balls 15 jump against the cover 30 is one of the attractive features of the toy. This noise is increased by using a plastic material for the cover 30 firmly secured to the hollow base 10. There is a drumming effect of the balls 15 against the sides of the cover 30 and the vibration produced also causes a drumming effect from the base 10.

The preferred embodiment of the invention has been illustrated and described but some features can be used alone or in different combinations without departing from the invention as defined in the claims.

What is claimed is:

1. A toy comprising a base, a row of sockets on top of said base and extending in a row lengthwise of the toy, each of said sockets having side walls in position to prevent displacement of an element in the socket lengthwise of the toy, separate actuators extending forward from the respective sockets, each of the actuators having a portion by which it is manually operated to cause the element in the associated socket to be projected upward out of the socket, a cover extending across the socket at a substantial distance above the elements, at least a portion of the cover being transparent, and the inside surface of the cover above at least some of the sockets having

a slope toward the space above another socket so that elements projected upward against the sloping surface are deflected lengthwise of the toy over other sockets.

5 2. A toy including a base, an array of different colored sockets on top of said base and extending in a row lengthwise of the toy, each of said sockets having side walls in position to prevent displacement of an element in the socket lengthwise of the toy, separate elements in the respective sockets, the elements being colored to correspond with the sockets in which they are located, actuators extending into the respective sockets, each of said actuators having a portion extending into the socket to a level in the socket substantially below the upper portions of the side walls of the socket, and having forwardly extending portions by which the actuators are operated to project the elements upward and out of their respective sockets, a cover that fits over the base and that extends both ahead and behind the sockets for enclosing the space above the sockets within which the colored elements are confined, said cover having at least a portion of its inside surface above the sockets sloped toward the space above other sockets so that elements projected against the surface are deflected lengthwise of the toy.

10 3. A toy comprising a base having a bottom and walls extending upward from the base to form a row of sockets, the walls along the fronts of the sockets having recesses in their upper edges, separate levers extending through the respective recesses in the front walls of the sockets, each of the levers having notches in its opposite sides engaged by the portions of the wall on each side of the recess for preventing horizontal displacement of the lever, the rearward portion of each lever extending across the bottom of its associated recess and the forward end of each lever extending beyond the front wall of the socket and comprising an actuating key for rocking the lever on the front wall of the socket as a fulcrum, separate displaceable elements resting on the levers in the respective sockets, a cover attached to the base and forming with the base a chamber of substantial size above the sockets, said cover having a portion that extends across the levers above the front walls of the sockets so as to prevent the levers from being lifted out of the recess in the front walls of the sockets, and said cover being transparent and shaped so that most regions of its inside surface above the sockets extend in directions that are at an angle to the direction in which the row of sockets extends.

15 4. A toy comprising a one-piece base with a plurality of sockets in its top surface and a continuous wall extending across the forward ends of the sockets, said wall having a recess in its upper edge in front of each of the sockets, a colored plastic lever extending across the bottom of each socket, and sloping downward toward the rearward end of the socket, each of the levers extending through the recess in the front wall, and outward beyond the front wall to provide an actuator key for rocking the lever about the bottom of the recess as a fulcrum, notches in opposite sides of the lever engaged by the portions of the front wall on opposite sides of the lever to hold the lever against transverse displacement, the levers in the respective sockets being of different colors, separate displaceable balls in the respective sockets, the balls being of different colors to correspond with the colors of the levers, and being

of a diameter less than the width of the sockets and substantially less than the fore and aft lengths of the sockets, a transparent dome having a bottom edge portion that fits into a groove in the top surface of the base, said dome having its lower edge portion rigidly secured to the base, and said dome having a portion of its lower edge extending along the front walls of the sockets at the upper ends of the recesses in the sockets for preventing the levers from being lifted out of the sockets, the dome having substantially parallel front and back walls joined by curved top and

side portions that are of continuous and symmetrical curvature about the center of the toy.
